MINE CAR

Hugh W. Sanford, Knoxville, Tenn., assignor to
The Sanford Investment Company, Wilming-
ton, Del., a corporation of Delaware

Application July 19, 1939, Serial No. 285,393

32 Claims. (Cl. 105—364)

1

The invention relates generally to mine cars or other vehicles and primarily seeks to provide certain new and useful frame and body structure combinations designed to simplify manufacture of cars of this character and provide a maximum of lading space therein for the same over-all dimensions of cars and in conjunction with cars having limited outside dimensions as well as required practical working clearances above the ground outside the wheels.

In the manufacture of mine cars it is, of course, desirable to make the cars as simple and sturdy in construction as is possible, and also to provide the maximum of lading space obtainable therein within the practical limits. One conventional means of providing added lading space is to equip the cars with side wing structures which project laterally beyond the wheels in a plane cutting the wheels. These low side wing extensions necessitate the building of hoods over the wheels and these hood structures sometimes seriously hamper the mounting and removal of wheel structures. It is also customary to provide inwardly and downwardly flared bottom portions in such side wing structures, these slopes downward towards the car sills being necessary in cars of the bottom dumping type to properly shed the lading into the bottom dump opening, and in cars of the rotary or end dumping type, to enable a low positioning of the inner limits of the wing bottoms and the relatively high positioning of the outer limits of said bottoms that may be essential to the provision of necessary roadbed clearances outwardly of the car supporting trackage. It is therefore an object of the invention to provide novel frame and body combination structures which will permit the mounting and removal of wheels and at the same time enable the positioning of the flared wing bottoms so that they start relatively close to the wheels and at the same time at unusually low levels, even at times intersecting the wheel axes outwardly of the upright or upwardly sloping sections of the sill-means, as the case may be, when these sections lie close to the adjacent car wheels, thereby providing considerably increased lading space as compared with conventional constructions of cars with the same over-all dimensions and road clearances.

Another object of the invention is to provide novel sill structures which facilitate the wing bottom positioning referred to and in which vertical sill walls are split and bent so as to provide vertical portions disposed within the hood limits, to be rigidly fastened to the hood walls and thus

2

give extra strength to the sills at the hood-box whereat the wheel hubs and axles would tend otherwise to reduce the strength of the sills and also to provide outwardly bent portions for supporting the wing bottoms, which may themselves slope at the same angle as the wing bottoms in which case they themselves may provide the beginning of the upward slope of what may be designated as wing lading bottoms. These outwardly bent portions are also tied in structurally with the side walls of the hood-box so as to give the added strength of the bent sill-section to the sill itself and at the same time to permit the wing bottoms to start at a very low position.

15 Another object of the invention is to provide a novel mine car frame structure in which the sills may be widely spread in a manner facilitating the provision of greater lading space between the sills while taking care of the strength 20 of the sills at the point where the wheel hubs and axles interfere with the continuity of the sill-structure.

25 Another object of the invention is to so design the novel equipments referred to so that they can be used in cars of the bottom-dumping, rotary or end-dumping types, and regardless of whether or not the two wheels of each pair of oppositely disposed wheels are mounted upon a single cross axle or upon two stub-axes.

30 With the above and other objects in view that will hereinafter appear, the nature of the invention will be more fully understood by following the detailed description, the appended claims, and the several views illustrated in the accompanying drawings.

In the drawings:

Figure 1 is a side elevation of a bottom dumping mine car embodying the invention.

Figure 2 is an end elevation of the car shown 40 in Figure 1.

Figure 3 is an enlarged side elevation of a fragment of the car of Figure 1 at the position of one of the wheel structures, parts being broken away and the wheel and axle being shown in dot and dash line phantom.

Figure 4 is a central vertical cross section of the parts shown in Figure 3.

Figures 5 and 6 are views generally similar to Figures 3 and 4 and illustrate a modified form of the invention in which the wheels are mounted on stub axles, a car of the bottom dumping type being shown.

Figures 7 and 8 are views similar to Figures 5 and 6 and illustrate the invention embodied in a car of the rotary dump, stub axle type.

Figure 9 is a detail perspective view of a fragment of one of the split and bent sill members.

Figures 10 and 11 respectively illustrate in side elevation and central vertical cross section another modified form of the invention presenting a novel frame and hood combination structure having provision for facilitating removal of the stub axle wheel structure.

Figure 12 is a view similar to Figure 11 and disclosing a further modification in which provision is made for recessing the innermost wheel hubs.

Figure 13 is a view similar in some respects to Figures 6 and 12 and illustrates the features of the simulated figures applied to car structures supported on cross axles.

Figure 14 is a fragmentary vertical cross-section taken through a side of a car intermediate the wheels thereof, and illustrating a form of side wing bottom stiffener.

Figure 15 is a view similar to Figure 14 and illustrates another form of side wing bottom stiffener and another form of gusset.

In the accompanying drawings there are illustrated several examples of practical embodiment of the invention.

In the form of the invention shown in Figures 1 to 4 of the drawings, the invention is shown as embodied in a mine car of the bottom dumping type including side walls 5 and end walls 6, 30 the side walls being inclined inwardly and downwardly so as to shed the lading through the bottom dump opening controlled by the bottom dump doors 7 which operate between the longitudinally disposed parallel spaced sill members 8 which define the bottom dump opening. The doors may be of any approved construction and the foremost door is pivoted as at 9 in the usual manner. The other doors have their pivot rods 10 disposed in hinge loops 11 formed on the door structures so that as each door is swung upwardly to its bottom closing position, the free edge thereof will suitably engage the adjacent pedestal structures and be moved forwardly so that the hinged edge of the respective door will move beneath and support the overlying free edge 12 of the next foremost door in the manner illustrated in Figures 1 and 3 of the drawings. The free edge of the rearmost door is supported by the usual automatically operable latching equipment generally designated 13. The side walls 5 may be reinforced at their upper edges by longitudinal angle members 14.

The car structure illustrated in Figures 1 to 4 of the drawings is of the 4-wheel, 2-axle type, and the sill members 8 are recessed as at 15 to clear the cross axles 16 on which the wheels 17 are mounted. It will be noted, also, by reference to Figures 1, 3 and 4 of the drawings, that the horizontal flanges 18 of the sill members are recessed as at 19 to straddle the wheel flanges and thus minimize the space intervening the inner faces of the wheels and the outer faces of the sill member vertical flange portions.

A plate or casting 20 is attached to each sill member at the position of each recess 15, and these elements are secured as at 21 to the vertical flange of the sill members. These elements 20 provide wider bearing surfaces for the axles and lugs engaged by transverse brace members to be referred to hereinafter. Each member 20 has an axle bearing aperture 22 therein and an outer face recess 23 for receiving the vertical flange portions lying at each side of the respective sill member recess 15 so as to additionally

facilitate close spacing of the wheels and sill members and the provision of a maximum of lading space intervening the inner faces of the sill member vertical flange portions.

The side walls 5 are cut away to accommodate the positioning of hood members 24 which overlie the wheel structures in the well known manner. Each hood structure 24 is welded in position, and secure attachment is facilitated by provision of suitable supporting brackets 25 secured to wall plates 26 which form sill-reinforcing arch means and inner closures for the hoods. These plates are secured as at 27 to the elements 28 and also by the same rivets 21 which secure the vertical flange portions of the sill members and the elements 20 in assembled relation.

Each opposed or cooperating pair of hood end closure plates 26 is joined in rigid assembly by a cross tie member 28 weld-secured to said plates 26 by aid of mounting brackets 29 and comprising a metal plate structure bent into inverted U-form and including downwardly extended lading shedding flange portions 30 which overlie the axle members 16 in the manner best illustrated in Figure 3 of the drawings.

It will be noted by reference to Figures 3 and 4 of the drawings that the vertical flange portions of the sill members extend full height within each hood structure so as to add this strength to the sill and so as to provide ample surface for the attachment of the elements 26 and 20. At each side of each hood structure, the sill members are split vertically as at 31 and are bent outwardly-upwardly to form attaching flanges 32 to which the side wall or wing bottom plating 5 is rigidly secured, and to provide a low start for the flare of the wing bottoms and increase the strength of the sill construction. This outwardly bent portion is normally welded to the vertical transverse side walls of the hood structures. It will be observed by reference to Figure 4 of the drawings that the plating 5 is extended inwardly beyond the sill members 8 as at 33 so as to overhang the door sill and shed lading thereover.

It is to be understood of course that the invention is not limited to any particular angle of presentation of the split and bent sill portions. The angular relation of the respective wall portions of the sill members depends entirely upon the form of side wing bottom to be used and attached to the split and bent sill portions and said portions may therefore lie horizontally or at various angles.

It will be observed by reference to Figure 3 of the drawings that each element 20 includes a camming or door wedging surface 34 which is engaged by abutment members 35 secured to the free edge portion of the particular door structure for wedging that door structure forwardly into its door securing position in the manner hereinbefore described.

In the form of embodiment of the invention illustrated in Figures 5 and 6, the invention is applied to a mine car of the 4-wheel, 4-axle type in which the cross axles hereinbefore referred to are supplanted by stub axles. In this embodiment of the invention, the sill attached plates or members are merely socketed or recessed as at 36 to receive the inner ends of the stub axles 37 upon which the wheels 38 are centrally mounted. The sill-reinforcing element and closure plate 39 for each hood structure 40 is opposed by a parallel spaced supporting plate 41 which is weld-secured within the hood struc-

5

ture by aid of suitable bracket members 42 and to which an axle bearing member 43 is rivet-secured as at 44. Each bearing member 43 includes an axle socket or recess 45 aligned with the previously mentioned recess or socket 36 and which completes the bearing for the respective wheel and axle structure 37, 38 with space sufficient to permit dropping of the axle provided at each end. Like the elements 26 the elements 39 are formed of very rigid steel plate forming a stiff girder at each wheel capable of resisting strains in all directions and which completely reinforce the sills where they are recessed at the wheel positions.

It is to be understood that in this form of the invention the same hood closure plate cross tie feature and the sill mounting and splitting features are provided as were described in connection with Figures 3 and 4, the principal difference being provision of the stub axle mounted wheels instead of the wheels being mounted on single cross axles. In this form of the invention, by removal of the brackets 43, the wheel and axle units 37, 38 can be readily canted and removed from the respective hoods.

In Figures 7, 8 and 9, there is illustrated an additional modification of the invention applied to a mine car of the rotary dump type in which the wheels are mounted on stub axles. In this form of the invention, the sill members 46 have their horizontal flanges 47 inwardly directed so as to form rigid supports for the bottom plating 48, and also so as to give horizontal flanges of full width and strength while at the same time increasing the distance between the upright portions of the sill means in such a fashion as to increase the width of the central lading bottom portions at this low level and thus increase the capacity of the car and at the same time obtain a design wherein oppositely disposed wing bottoms may start from positions that are widely spaced apart and which are at low levels thus, again, increasing the capacity of the car. As in the forms of the invention previously described, the vertical flange portions of the sill members are recessed as at 49 to clear the wheel hubs and extend full height as at 50 within the hood structures.

Beyond each hood structure the vertical flange portion of each sill member is split as at 51 and bent outwardly-upwardly to provide flare bottom attaching flanges 52 to which the flared portions 53 of the respective side wing bottom structure is attached, said side wing bottom structure including a horizontal portion 54 which is rigidly secured to the respective body angle 55, thereby providing a wing bottom disposed in two distinct planes whereby a larger capacity for the car is obtained in combination with the required road clearances and means facilitating removal of the wheels. Side wall plating 56 is secured to and extends upwardly from each angle side-wall stiffening member 55 and preferably terminates in a reinforcing rebent portion 57 best shown in Figure 8 of the drawings.

At the position of each wheel, an angle iron flange member 58 is provided, and its upright flange portion serves as a support for a hood member 59 adapted to overlie and protect the particular wheel portions, and the slope of the angle upward gives a draft which prevents the lading from wedging so that it will not discharge readily when the car is rotated. This construction also obviates an extra bend in the hood-

6

cover and at the same time increases the capacity of the car somewhat. Each hood structure is likewise attached as at 60 to the side wing bottom plating 54, and as at 61 to a hood closure and sill-stiffening plate 62 which is cupped inwardly as at 63 to receive the respective wheel hub 64 to thereby enable a positioning of the plate 62 and sill member vertical flange portion very close to the wheel flanges, thereby providing for a maximum of lading space intervening said plates 62. The plate member 62 is secured as at 65 to the vertical flange portions 50 of the sill members disposed within the limits of the respective hood structure, either directly or with fillers.

An axle bearing member 66 is secured to and depends from each of the flange members 58 and is suitably socketed or recessed as at 67 to receive the outer end of the particular stub axle, the inner end of the respective stub axle being received in a suitable socket 67a in a reinforcing element 66a secured to the respective closure plate 62, both sockets providing space to permit axles to drop on uneven track.

In Figures 10 and 11 of the drawings, there is illustrated still another form of mine car of the rotary dump type including stub axle wheel mountings. In this form of the invention, the sill members 68 have their horizontal flanges 69 directed inwardly to rigidly support the bottom plating 70.

The vertical flange portions of the sill members are recessed as at 71 to receive the inner ends of the stub axles, and so as to permit these ends to penetrate the upright plane of the outside of the upright portions of the sill-means as these sill-means extend from an axle towards the adjacent end lading wall of the car, and at the position of each recess a hood closure plate 72 is secured to the inner face of each said vertical flange portion. The sill members also have inner wheel boxes 73 attached thereto at the position of each recess, said boxes having recesses or sockets 74 therein to receive the inner ends of the stub axles 75 which centrally support the wheels 76. It will be noted that these boxes are fastened directly to the vertical portions of the sills below the axle level.

The outer end of each stub axle is mounted in a recess or socket 77 in a bracket member 78 riveted to the supporting plate 79 which is opposed to the respective hood closure plate 72. By cutting the rivets fastening the element 78 to the element 79, a wheel and axle can readily be removed from the car. A hood structure 80 overlies each wheel and is welded to the respective plates 72 and 79 and to reinforcing angle members 81. The hoods are also secured through the medium of angle irons 82 to the side wall structures 83, each of which includes an angle member 84, the horizontal flanges of which angle members serve to support the side wing bottom plating 85 which is flange secured as at 86 to the vertical wall portion of the sill members 68. The hood members 80 are also secured as at 87 to the side wing bottom plating 85 as shown in Figure 10 of the drawings.

In Figure 12 there is illustrated an additional modification of the invention which is constructed identically with the forms shown in Figures 10 and 11 except that each hood end closure and reinforcing plate 88 is inwardly cupped as at 89 to receive the respective wheel hub 90 and is fastened to the upright portion of the sill, and the vertical flange portions of each sill are recessed to a greater extent as at 91 so as to re-

ceive the wheel hubs. By this cupping of the closure plates 88 the sill members may be positioned very close to the wheel flanges with the upright portions of each sill lying in a plane cutting the wheel hubs and a maximum of lading space intervening the axle members is thus provided.

In Figure 13 the structure is similar to that disclosed in Figure 12 except that in this illustration the axle 92 is of the cross-over type and the outer boxings and plates necessary to support the stub axles of Figure 12 are eliminated. In this form, the hood end closing and sill-reinforcing plates 93 are cupped as at 94 to receive the wheel hubs 95 and the axle bearing boxes 96 are provided with axle bearing apertures 97 and suitably support a cross tie member 98 which overlies said axle and serves as an axle housing as well as a reinforcing support for the bearing boxes 96. The sill members are recessed as at 99 to receive the wheel hubs and the cupping of the plates 93 serves to provide greater lading space intervening opposed sill members in the same manner described in connection with Figure 12. It will be observed that suitable space is provided under the hood structure and outwardly of the plate 93 to permit easy removal of the wheel from the respective end of the cross-over axle 92.

In Figure 14 there is illustrated a fragmentary vertical section between wheels of a car structure in which the side wing bottom is attached at a low point to the outwardly and upwardly bent portion 100 of the sill member 101 and is bent to present two distinct lading supporting planes one thereof 102 being inclined upwardly and outwardly from the sill portion 100 and the other 103 being horizontally disposed. In order to assure against disruption of the angular relation of the wing portions 102 and 103 by constant pressure of the lading, flare or wing stiffeners may be secured at intervals to the wing bottom and sill structure in the manner shown in this figure. In this illustration the stiffener comprises a flange body portion 104 which is secured to the wing bottom, a flange body portion 105 which is secured to the sill structure, and one or more strengthening webs 106 joining said flange body portions.

Figure 15 is a view similar to Figure 14 and illustrates further modified forms of flare or wing stiffener and gusset structures. In this form of the invention each stiffener is in the form of a continuous strap or bar 107 which is secured to the flare or wing bottom and to the sill member. The gusset 108 interposed between the angle or flange member 109 and the side wall structure includes a flange body portion 110 which is secured to the side wall structure 111, and a web portion 112 which is welded as at 113 to said angle member 109. With this form of gusset, a filler member 114 is interposed between the gusset and the angle member 115 forming a part of the side wall structure.

This gusset structure differs from the gusset embodied in Figure 8 in form alone and not in function. It will be noted that the gusset 116 of Figure 8 also includes a web portion 117 and flange body portions 118 which are shaped to tightly engage the side wall, wing bottom and angle member portions to which they are rigidly secured.

If desired, each gusset may take the form of a single thickness flat plate or web 119 disposed vertically and welded at its edges as at 120 to the engaged portions of the side wall, the wing

bottom and the angle member. See Figure 14.

The function of the gussets is the same however formed, and it will be noted that each gusset stands over the wheel and axle axis with which it is associated. These elements cooperate with the cross tie members in greatly strengthening the car laterally. The sill means are tied in with the hood structures and the wing bottoms and with the cross tie members and the side wall structures, assuring against spreading of the car sideways.

The splitting and bending of the sill members in the manner shown provides practically full strength of sills between end walls and wheel hoods and allows the outwardly and upwardly bent sill portions to lie in a plane which when extended would pass through the wheel hubs, while, at the same time, at a point where the wheel hubs intervene the straight section of the sill passes inside the wheel hubs, and provides the straight vertical height past the wheel hubs at a point where it does not interfere with the low floor between the ends of the wheel hubs and the adjacent ends of the car, or between the contiguous wheel hubs themselves.

In the stub axle car, as shown in Figure 8 for example, there is provided a design in which the horizontal flanges of the sills are turned inwardly instead of outwardly as in Figure 3, and thus although the vertical walls of the sills are cut away at the wheel hubs, nevertheless the vertical walls between the wheel hubs and adjacent ends of the car lie altogether in an upright plane cutting through the wheel hubs. Moreover by bending the sills in the manner shown in Figure 3, a low flare is obtained which increases lading capacity without sacrificing strength of sill. The bent sill portions being welded at their ends to the hood structures, a stronger structure is provided than would result if the sills were made normally without splitting and bending.

By "stub axles" reference is made to the form of axles shown in Figures 6, 8 and 12 upon which individual wheels are mounted, as distinguished from the through axles of Figure 14 each of which extends transversely across the car and beyond the sill structures and each of which carries two wheels one at each end thereof.

The wheels herein illustrated all include the flanges usually employed in railway rolling stock. In cars embodying the invention and employing flanged wheels, the treads of the wheels may be defined as the portions of the wheel faces outside the flanges and which bear against the track rails, whereas in vehicles which employ wheels devoid of flanges the treads of such wheels may be defined as the portions of the wheels which come in contact with the ground and support the wheels on the ground.

The novel sill members herein disclosed each include an upright wall and a horizontal, outwardly or inwardly directed flange. The upright wall is of single dimension or depth, but it will be observed by reference to Figure 9 of the drawings that this single depth wall includes portions which lie in different planes, namely a vertical, full depth portion opposed to each wheel, and a partial depth portion intervening the wheels and the ends which are angled upwardly and outwardly.

It has been estimated that each extra cubic foot of lading capacity provided in a mine car by embodiment of the principles of invention herein disclosed saves more than twenty dollars during the average life of that car.

It is of course to be understood that the details of structure and arrangement of parts may be variously changed and modified without departing from the spirit and scope of my invention.

I claim:

1. In a mine car, spaced longitudinal sill-elements each including substantially upright lading space defining portions that extend substantially from one end of the car to the other, car axles disposed transversely of the sill-elements, car wheels on said axles located close to and outside said sill-elements, a lading-supporting bottom structure located between said sill-elements and disposed at least in part beneath the horizontal plane of the axes of the car wheels, and car body structure including wheel hood structures and including also outwardly extending and upwardly sloped side-wing-bottom portions in rigidly secured relation with said sill-elements and intersecting the said horizontal plane outwardly of the outside of the said substantially upright portions of the sill-elements.

2. In a mine car, spaced longitudinal sill-elements of rolled metal each including substantially upright first portions that extend substantially from one end of the car to the other; car axles disposed transversely of the sill-elements, car wheels on said axles located close to and outside said substantially upright sill-element first portions; a central lading bottom at least in part located below the horizontal plane of the axes of the car wheels; car body structure including side wing bottom portions and also hood structures closely overlying the car wheels close to the inside of each wheel and with inside upright closure walls; each said sill-element also including a second longitudinal portion being an upright extension of one of the said first upright portions where it passes a car wheel, and third longitudinal portions where these said upright portions are located away from the hood-structures, said third portions extending outwardly from the said first portion at an angle to the said first upright portion, the said third portions serving at least in part as engagement surfaces for adjacent parts of the said side wing-bottom portions.

3. A mine car structure as defined in claim 1, in which the length of the upright lading space defining portion of each sill member spanning the space between the limits of each hood structure in the direction of the length of the respective sill member extends in a single upwardly extending plane and portions of said sill member not spanning a space between limits within a hood structure are bent at an angle to serve as engaging flanges for the lower edges of the wing bottom portions and in which said axle members comprise stub axles, there being one stub axle for each wheel, and wherein there is included means by which each said axle supports the body outside of the respective wheel on said axle, and means by which the end of each axle inwardly of the respective wheel supports the body structure at least in part through the upright lading space defining sill portion spanning the space between the limits of the adjacent hood.

4. In a bottom-dumping mine car, longitudinal sill members disposed in spaced relation and substantially parallel throughout their length and each including an upwardly extending lading space defining flange portion and an outwardly directed flange portion, axle members disposed transversely of the sill members, wheels on said axle members, lading supporting drop doors

located between said sill members and disposed at least in part beneath the horizontal plane occupied by the wheel axes, and body structure including a hood structure overlying each wheel and side wing portions in rigidly secured relation with the sill members and outwardly and upwardly flared and intersecting the horizontal plane occupied by the wheel axes outwardly of said sill member upwardly extending flange portions, each said hood structure including an inner closure wall, and each said sill member having axle accommodating clearances in its upwardly extending flange portion, a sill reinforcing member opposed to each hood structure closure wall and bearing upon the axle under said hood structure, and means securing each reinforcing member and closure wall to the upwardly extending flange portion of the adjacent sill member, said upwardly extending flange portions at points outside the hood structures being inclined to the vertical and to the remainder of said upwardly extending flange portions to serve as engaging flanges for the lower edges of the wing bottom flare.

5. In a mine car, longitudinal sill members disposed in spaced relation and substantially parallel throughout their length and each including an upwardly extending lading space defining flange portion and a substantially horizontal flange portion, axle members disposed transversely of the sill members, wheels on said axle members, lading supporting means located between said sill members and disposed at least in part beneath the horizontal plane occupied by the wheel axes, and body structure including a hood structure overlying each wheel and side wing portions in rigidly secured relation with the sill members and outwardly and upwardly flared and intersecting the horizontal plane occupied by the wheel axes outwardly of said sill member upwardly extending flange portions, each said hood structure including an inner closure wall, a sill reinforcing member opposed to each hood structure closure wall and bearing upon the axle under said hood structure, and means securing each reinforcing member and closure wall to the upwardly extending flange portion of the adjacent sill member, said upwardly extending flange portions at points outside the hood structures being inclined to the vertical and to the remainder of said upwardly extending flange portions to serve as engaging flanges for the lower edges of the wing bottom flare, each said wheel including an inwardly directed hub, said upwardly extending sill flange portions having clearances therein large enough to receive said wheel hubs, and said hood structure closure walls being cupped inwardly to receive said wheel hubs and permit the upwardly extending sill flange portions to be placed very close to the upright planes of the inside edges of the tread surfaces of said wheels.

6. In a bottom-dumping mine car, spaced longitudinal sill-elements each including a substantially upright lading space defining portion continuous from end to end of said car, car axles disposed transversely of the sill-elements, car wheels on said axles located close to and outside said sill-elements, car body structure including wheel hood structures and outwardly extending and upwardly sloped side wing bottom portions in rigidly secured relation with said sill-elements and intersecting the horizontal plane of the axes of the wheels outwardly of the outside of the said substantially upright portions of the sill-

70

elements, and drop bottom door structures located between said sill-elements and disposed at least in part beneath the said horizontal plane and forming substantially continuous lading seals with the continuous substantially upright sill-element portions.

7. In a mine car, wheels and individual stub axles for said wheels at each side of the car, a sill member extending longitudinally of the car along each side of the car, a central lading bottom substantially closing the space between the sill members and cooperating with the sill members in forming a center bottom lading space extending below the plane in which the wheel axes are located, a side wing bottom extending laterally-outwardly from each sill member at a level higher than that of the center bottom and having openings therethrough through which said wheels extend upwardly, wheel hooding structures overlying said wheels and closing the wing bottom openings and bearing means for each stub axle, each said sill member including an upright center bottom lading space defining surface disposed inwardly of the wheels at the particular side of the car and at least in part beneath the horizontal plane in which the wheel axes lie and so close to adjacent wheels as to lie in an upright plane which intersects the stub axles at that side of the car, thereby to provide wider than conventional spacing between said lading space defining surfaces and resultant greater than conventional lading capacity in said center bottom lading space.

8. In a wheeled car including a lading body structure and a lading bottom, the combination of axles for the wheels, at least two spaced-apart sill-means extending in substantially parallel relation longitudinally of the car and lying between the innermost limits of the treads of wheels and which have outwardly directed substantially horizontal portions and other upwardly extending portions, the said sill-means being in themselves sufficiently strong to support without objectionable end-dropping or twisting or warping the lading in the ends of the car as well as the lading in the sides of the car, said bottom structure including a central longitudinally extending lading bottom-means located between oppositely disposed sill-means and having top surface-portions at least in part located below the horizontal plane of the axes of the wheels and a wing lading-bottom outside of each of two oppositely disposed sill-means, each said wing bottom being sealed with respect to the adjacent sill-means and extending outwardly and upwardly beyond the adjacent sill means and lying in a plane cutting the adjacent wheels, and means covering the wheels to prevent leakage of lading, said upwardly extending sill-means portions lying in at least two planes one of which is upright adjacent each wheel and another of which is acutely inclined laterally with respect to said one plane and cooperating with the adjacent wing bottom in effecting said seal, and each upwardly extending portion in the upright plane being disposed so close to the adjacent wheel as to place the associated acutely inclined portion in position for traversing the upright plane in which the flange of said adjacent wheel is located, thereby to space the upwardly extending sill-means portions at opposite sides of the car a greater than conventional distance apart and provide a greater than conventional amount of lading space between said two oppositely disposed sill-means.

9. A car structure as in claim 1, in which the

hood structures each includes a longitudinal lading sealing wall disposed inwardly of the wheel structures, and in which said upright sill-element portions are disposed very close to the wheel hubs and are in rigidly secured relationship with said hood walls.

10. In a car structure of the character described, a sill member comprising a substantially horizontal flange portion and an upwardly-extending wall, said wall having axle accommodating openings therein and extending full height a limited distance in each direction from each opening and having the portions thereof endwise of each full height portion disposed substantially vertically throughout only the lower portion of their height and on an upward-outward incline throughout the remaining or upper portion of their height thereby to provide additional sill strength and inclined wing bottom supporting portions to which wing bottoms can be attached at a level below the full height of said full height portions.

11. In a wheeled car including a lading body structure and a lading bottom drop-door structure, the combination of axles for the wheels, at least two spaced-apart sill-elements in part between oppositely disposed wheels, and having upwardly extending portions cut by the horizontal plane of the axes of the wheels opposite the wheels and having lower upwardly extending portions extending continuously in substantially parallel relation substantially from end to end of the lading body of the car, and the said sill-elements having outwardly directed lower stiffening flanges, and the said sill-elements being in themselves sufficiently strong to support without objectionable end-dropping or twisting or warping the lading in the ends of the car as well as the lading in the side of the car, a central lading bottom structure extending longitudinally between oppositely disposed sill-elements and having top surface portions at least in part located below the horizontal plane of the axes of the wheels and a wing lading-bottom outside of each of two oppositely disposed sill-elements, each said wing bottom being sealed with respect to the adjacent sill-element and extending outwardly and upwardly beyond the adjacent sill-element in an upward slope sufficient to assure the discharge of superimposed lading by gravity through the said bottom drop-doors when dropped and lying in a plane cutting the adjacent wheels, and means covering the wheels to prevent leakage of lading, and a portion of each said wing bottom as it passes outwardly and upwardly away from an adjacent sill-means lying in a plane which intersects the horizontal plane of the wheel axes at a point which is located outside of the plane occupied by portions of the outside surface of the lower upwardly extending portions of the adjacent sill-elements.

12. In a mine car wherein is provided supporting wheels, sill elements extending longitudinally of the car between opposed wheels, wheel-hood-structures, wing lading bottoms extending outwardly and upwardly from top portions of adjacent sill-elements where these top portions lie between car wheels and adjacent ends of the car, a central longitudinal lading bottom lying at least in part below the horizontal plane of the axes of the car wheels, said sill-elements being cut by the horizontal plane of the axes of the wheels of the car and being separate from the adjacent outwardly extending lading bottom of the car and each constituting a stiff metal angle

13

having an outwardly extending bottom flange-portion and a substantially upright flange-portion, and part of each said upright flange-portion extending longitudinally substantially from end to end of the lading bottom of the car close to the inside of an adjacent car wheel hood-structure and the said element having the portions of its otherwise upright flange-portion bent outwardly between each car wheel and the adjacent end of the lading body and between car wheels along a line below full height of the portions of the upright flange-portion lying opposite wheels whereby the upright height of the said outwardly bent flange portions is lowered in the location in which the respective wing lading bottom extends from top portions thereof, and whereby the adjacent said wing lading bottom meets the top portions of the adjacent sill-element at a low level to provide larger lading capacity in the car.

13. A mine car structure as defined in claim 12 in which each hood structure cuts through the plane of the adjacent wing-bottom, each said hood-structure having a longitudinal and substantially upright wall passing close to the inside of the wheel hooded by it, and having another transverse substantially upright wall extending outwardly from the said longitudinal wall, and the said sill-element having portions rigidly secured to the said longitudinal wall and other portions rigidly secured to the said transverse wall.

14. In a mine car, a lading body, supporting wheels, two parallel metal sill-elements extending longitudinally and at least in part integrally substantially from end to end of the lading body to provide at least a major part of the stiffness needed to carry the lading load in the end of the car, each of said sill-elements where opposite said wheels being in flange-sections disposed in two general planes the first one of which is substantially upright and the second one of which is substantially horizontal, and the sill-elements where not opposed to the said wheels lying in flange-sections in three planes two of which are those already referred to and the third plane section extending outwardly, said sill-elements being placed with their upright sections so close to adjacent wheels that their third plane sections cut across and extend beyond the plane in which the adjacent car wheel flanges are located whereby greater stiffness of sill against warping and twisting is obtained between car wheels and the adjacent ends of car, and the upright section from which said third plane section extends outwardly being of lesser height than the upright section opposite said wheels.

15. A structure as defined in claim 14 wherein are provided hood-structures overlying the wheels and having substantially upright longitudinal and transverse walls and wherein increased stiffness of sills is provided where the flange-sections occupy two general planes only by their being rigidly attached to the substantially upright longitudinal walls of the said hood-structures.

16. A structure as defined in claim 14 wherein are provided hood-structures overlying the wheels and having substantially upright longitudinal and transverse walls and wherein increased stiffness of sills is provided where the flange-sections occupy three general planes by the rigid attachment of one end of that portion of a sill-section lying in the third plane to the upright transverse walls of an adjacent hood-structure.

14

17. A structure as defined in claim 14 wherein said second sections of the sill-elements which lie in the substantially horizontal plane extend outwardly from the lower portion of said first sections and at a level which is below the horizontal plane of the axes of the car wheels.

18. In a drop bottom mine car, car axles, car wheels, two parallel longitudinal rolled metal sill-means extending from above down through the horizontal plane of the axes of the car wheels, lading body structure including wing lading bottoms shaped so that when the doors are dropped all the lading of the car is discharged by gravity through the opening thus provided, a plurality of drop doors which when closed seal the central longitudinal area of the car, the said sill-means having substantially upright first portions passing in integral section substantially from end to end of the lading body of the car in a straight line and close to and between oppositely disposed car wheels, and the first said portions being in lading sealing relationship with at least part of the adjacent edges of closed drop doors, and having second portions of the said sill-means which are located below the said plane and which extend outwardly from the bottom of the said first portions to provide stiffening flanges, and having third portions of each of the said sill-means extending outwardly and upwardly from the upper part of said first portions where these first portions are located away from the places in opposition to the car wheels, and the said third portions lying in planes cutting the adjacent car wheels below the top surfaces of the treads of the said car wheels and lying at an angle to the horizontal greater than the angle of repose of the lading in the car whereby the said third portions serve at least in part as portions of the wing lading bottom structures for deflecting some of the superimposed lading to the place of discharge between the dropped doors, and wheel hooding structures which are in rigidly secured relationship with the said sill means and which stiffen the sill-means against warping and twisting.

19. In a car structure of the character described, a longitudinal sill member comprising a substantially horizontal flange portion and an upwardly extended wall, said upwardly extended wall being vertically split in a transverse plane downwardly from its upper extremity and being bent laterally throughout a portion of its length on a line below its upper extremity commencing at said split whereby to provide two portions of said upwardly extended wall lying in different planes one unbent and substantially vertical for opposition to a wheel and another angled outwardly with relation to the first to provide additional sill strength and for attachment with a wing bottom at a level lower than the upper extremity of said unbent portion.

20. In a mine car, wheels having inwardly directed hubs, individual stub axles for said wheels, a sill member extending longitudinally of the car along each side of the car, each said sill member including a substantially horizontal flange and an upwardly extending wall portion disposed at least in part beneath the horizontal plane in which the wheel axes lie, a central lading bottom substantially closing the space between the sill members and cooperating with the innermost faces of the upwardly extending sill member wall portions in defining a center bottom lading space, a wing bottom extending laterally-outwardly from each sill member at a level higher

than said center bottom, said upwardly extending sill member wall portions being disposed so close to adjacent wheels that the innermost faces thereof lie in an upright plane which intersects the wheel hubs at that side of the car, and bearing means for each stub axle attached in part to a sill member and in part to other parts of the car structure.

21. In a mine car, spaced longitudinal sill-elements, axle members disposed transversely of the sill-elements, wheels on said axles, lading supporting means closing the space between the sill-elements and disposed at least in part beneath the horizontal plane occupied by the wheel axes, and body structure including wheel hood structures and side wing bottom portions in rigidly secured relation with said sill-elements, each said sill-element comprising a stiff metal angle having a substantially horizontally extending bottom flange and an upwardly extending flange-portion extending longitudinally from end to end of the body structure, each said upwardly extending flange-portion being substantially vertically disposed throughout its full height within the lengthwise limits of the hood structures at the same side of the car and having those portions thereof located between said hood structures and those portions thereof located between ends of the body structure and adjacent hood structures inclined outwardly-upwardly throughout a portion at least of the depth thereof whereby the depth of the upwardly extending flange-portion is reduced between said hood structures and between hood structures and adjacent ends of the body structure, said side wing bottom portions being secured to the outwardly-upwardly inclined reduced depth sill-element portions thereby to provide larger lading capacity in the car.

22. A mine car structure as defined in claim 21, in which each hood structure cuts through the plane of the adjacent wing-bottom and includes a longitudinal and substantially upright wall passing close to and inwardly of the wheel hooded by it and another transverse substantially upright wall extending outwardly from said longitudinal wall, and in which the adjacent outwardly-upwardly inclined portion of the respective upwardly extending sill flange-portion is rigidly secured to the respective transverse upright hood structure wall.

23. A mine car structure as defined in claim 21, in which each hood structure cuts through the plane of the adjacent wing-bottom and includes a longitudinal and substantially upright wall passing close to and inwardly of the wheel hooded by it and another transverse substantially upright wall extending outwardly from said longitudinal wall, and in which the upwardly extending sill flange-portion is split downwardly from its top edge at the position of each hood structure transverse wall in order to facilitate shaping of the outwardly-upwardly inclined portion of the upwardly extending sill flange-portion and each said outwardly-upwardly inclined portion is rigidly secured to the respective transverse wall at the respective split.

24. In a mine car, spaced longitudinal sill members each including upwardly extending and substantially horizontal flange portions, axle members disposed transversely of the sill members, wheels on said axles, a central lading bottom substantially closing the space between said sill members, and body structure including side walls, a hood structure over each wheel and side

wing bottom portions sealed with respect to said sill members and side walls, each said sill member upwardly extending flange portion extending upwardly full height in a single plane throughout each portion thereof which spans the space between the limits of a hood structure in the direction of the length of said sill member and other upwardly extending flange portions of each said sill member away from the hood structures being bent outwardly at an angle along a line disposed lower than said full height for sealing association with a wing bottom just beyond each hood structure in the direction of the length of the car in each direction, each hood structure being weld-secured to a sill member at the position of each outward bend therein adjacent the respective hood structure.

25. In a mine car, wheels and individual stub axles for said wheels at each side of the car, wheel hooding structures overlying the wheels, stub axle bearing means, a sill member at each side of the car and extending longitudinally of the car at least in part beneath the stub axles, said bearing means being attached at least in part to said sill members, a central lading bottom substantially closing the space between the sill members, side and end wall structures, side wing bottom structures sealing those portions of the spaces between each sill member and the adjacent side wall structure not sealed by said hood structures, said side wing bottoms being formed of plating portions bearing angular relation one to another with portions thereof disposed in planes intersecting the upright planes in which the wheel flanges are located at points below the level of the wheel axes, and the portion of each wing bottom laterally-outwardly of the hooding structures at respective sides of the car being continuous from end to end of the car and being located above the horizontal plane occupied by the stub axle axes, and stiffener means conforming to the angular shape of and secured to the side wing bottom structures and to the sill members for retaining the angular relation of and preventing straightening out of said plating by downward pressure of the supported lading, said stiffener means being in rigid attachment-relationship with said plating.

26. In a mine car, car wheels and individual stub axles for said wheels at each side of the car, longitudinally extending sill-elements inside oppositely disposed car wheels, bearing means for said stub axles attached at least in part to said sill-elements, a central lading bottom lying at least in part below the horizontal plane of the axes of the car wheels and substantially closing the space between the sill-elements and cooperating with said sill-elements in forming a center bottom lading space extending below the plane in which the wheel axes are located, a side wing bottom extending laterally-outwardly from each sill-element at a level higher than that of the central lading bottom and having openings therethrough through which said wheels extend upwardly, wheel hooding structures closely overlying the car wheels and closing the wing bottom openings and with inside longitudinal closure walls close to adjacent wheels, each said sill-element including an upwardly extending center bottom lading space defining surface disposed at least in part beneath the horizontal plane in which the wheel axes lie and so close to adjacent wheels as to lie in an upright plane which intersects the stub axles at that side of the car, thereby to provide wider than conven-

17

ional spacing between said lading space defining surfaces and resultant greater than conventional lading capacity in said center bottom lading space.

27. In a mine car, spaced longitudinal sill-elements each including lading space defining portions that extend substantially from end to end of the lading space in the car, car axles disposed transversely of the sill-elements, car wheels on said axles located close to and outside said sill-elements, a lading-supporting bottom structure located between said sill-elements and disposed at least in part beneath the horizontal plane of the axes of the car wheels, and car body structure including wheel hood structures and including also outwardly extending and upwardly sloped side-wing-bottom portions in rigidly secured relation with said sill-elements and intersecting the said horizontal plane outwardly of said lading space defining sill portions.

28. In a mine car, a sill member comprising a rolled steel shape having a substantially horizontally disposed bottom flange portion and an upright wall portion, said upright wall portion lying in a single plane throughout a portion of its length and in two planes throughout another portion of its length one of said two planes extending uprightly from said bottom flange and the other of said two planes extending upwardly and outwardly from said one plane at an angle intersecting said single plane.

29. In a mine car, wheels and individual stub axles for said wheels at each side of the car, wheel hooding structures overlying the wheels, a sill member extending longitudinally of the car along each side of the car, each said sill member including an upright wall portion disposed at least in part beneath the horizontal plane occupied by the wheel axes and at least in part presenting a central lading space defining surface disposed so close to adjacent wheels as to lie in an upright plane which intersects the stub axles at that side of the car, a central lading bottom substantially closing the space between the sill members, a wing bottom extending outwardly from each sill member at a level higher than the central lading bottom, and bearing means for each stub axle attached in part to a sill member and in part to other parts of the car structure.

30. In a mine car, wheels and individual stub axles for said wheels at each side of the car, wheel hooding structures overlying the wheels, sill members extending longitudinally of the car between oppositely disposed car wheels, each said sill member including a substantially upright wall portion disposed at least in part beneath the horizontal plane occupied by the wheel axes and serving at least in part as a lading retaining wall of a central lading space, each said lading retaining wall lying in a plane which intersects the adjacent stub axle at the respective side of the car thereby to provide maximum lading capacity or width between said lading retaining walls, a central lading bottom substantially closing the space between said lading retaining walls, a wing bottom extending outwardly from each sill member at a level higher than the central lading bottom, and bearing means for said stub axles.

31. In a mine car, wheels and individual stub axles for said wheels at each side of the car, wheel hooding structures overlying the wheels, sill members extending longitudinally of the car

18

between oppositely disposed car wheels, each said sill member including a substantially upright wall portion disposed at least in part beneath the horizontal plane occupied by the wheel axes and serving at least in part as a lading retaining wall of a central lading space, said lading retaining walls being spaced apart a greater distance than are the opposed ends of stub axles disposed at opposite sides of the car thereby to cause said lading retaining walls to intersect the stub axles close to and inwardly of the wheels at the respective sides of the car and define between them a central lading space of maximum width, a central lading bottom substantially closing the space between said lading retaining walls, a wing bottom extending outwardly from each sill member at a level higher than the central lading bottom, and bearing means for said stub axles.

32. In a drop bottom mine car, two sill members extending in parallel spaced relation longitudinally of the car, car axles intersecting said sill members, car wheels on said axles, a plurality of drop doors which when closed seal the central longitudinal area of the car between the sill members, lading body structure including wing lading bottoms shaped so that when the doors are dropped all the lading in the car is discharged by gravity through the opening thus provided, and hood structures over said wheels, each said sill member comprising a mill rolled steel shape having a substantially horizontally and outwardly extending bottom flange portion and a substantially upright wall portion, said substantially upright wall portion lying in a single plane at each portion thereof intersected by an axle and in at least two planes throughout other portions thereof extending endwise between said single plane portions and between said single plane portions and the sill member ends, one of said at least two planes of each of said other portions extending uprightly from said bottom flange and another of said at least two planes of each of said other portions extending upwardly and outwardly from said one plane at an angle and intersecting said single plane and forming a support for the adjacent wing bottom at a level below the top of said single plane upright wall portion.

HUGH W. SANFORD.
